W. E. FIELDS.

TROLLEY HARP.

APPLICATION FILED JAN. 15, 1921.

1,432,452.

Patented Oct. 17, 1922.

Inventor

William E. Fields,

By F. A. Colford

Attorney

UNITED STATES PATENT OFFICE.

WILLIAM E. FIELDS, OF WOODMONT, MARYLAND, ASSIGNOR OF ONE-THIRD TO JED GITTINGS, OF MONTGOMERY COUNTY, MARYLAND, AND ONE-THIRD TO CHARLES PAYNE, OF WASHINGTON, DISTRICT OF COLUMBIA.

TROLLEY HARP.

Application filed January 15, 1921. Serial No. 437,510.

To all whom it may concern:

Be it known that I, WILLIAM E. FIELDS, a citizen of the United States, residing at Woodmont, in the county of Montgomery 5 and State of Maryland, have invented certain new and useful Improvements in Trolley Harps, of which the following is a specification.

The present invention relates to trolley 10 harps, and has more particular reference to a structure of spindle mounting for a trolley wheel whereby a lubricant may be more easily maintained on the journals of the spindle.

15 An object of the present invention is to provide an improved structure of trolley harp which is relatively light in weight, is strong in construction, and which provides lubricant chambers and passages to which 20 access may be quickly had for refilling.

Another object of the invention is to provide a trolley harp having a shaft or spindle support which may be easily and quickly opened so that the shaft or spindle may be 25 easily withdrawn for separating the parts, and wherein the parts are all held in position by a single fastening means.

The above, and various other objects and 30 advantages of this invention will be in part described in and in part understood from the following detailed description of the present preferred embodiment, the same being illustrated in the accompanying drawing, wherein:

35 Fig. 1 is a side elevation of a trolley harp constructed in accordance with the present invention;

Fig. 2 is a side elevation thereof;

40 Fig. 3 is a vertical fragmentary section through the same on the line 3—3 of Fig. 2, looking in the direction of the arrows and with the wheel removed;

Fig. 4 is a fragmentary side elevation taken oppositely to Fig. 2 of the harp, showing the fixed bearing; and

45 Fig. 5 is a detail perspective view of the removable bearing block for the harp.

Referring to the drawing, the main body 50 portion of the device is in the form of a casting having a shank 10 adapted to be seated in the upper end of a trolley pole or the like and which is provided with a pair

of arms 11 and 12 branched from the upper end of the shank 10 and having an apertured ear 13 at the juncture of the arms extending 55 from one side of the harp to which a cable or the like may be attached.

The arm 11 is of a hollow construction as shown to advantage in Figs. 3 and 4, and provided with side walls 14 and an inner 60 wall 15 which is substantially flush with the inner edges of the side walls for bracing the same. The upper end of the arm 11 is provided with a bearing portion 16 extending entirely through the arm and in which is 65 fitted a brass or bushing 17 provided with a flange 18 upon its inner end adapted to engage the inner wall 15 of the arm.

The arm 11 is provided with a front wall 19 above the bearing 16, the wall 19 forming together with the side walls 14 and the inner wall 15, a chamber or compartment 20 adapted to receive a lubricant. The chamber 20 may be closed at its upper end by a piece of waste 21 and the front wall 19 has 75 at its upper edge an inwardly projecting bar or shoulder 22 beneath which the piece of waste 21 is adapted to be packed for holding the waste in the chamber 20.

The bearing 16 is provided with a passage 80 or opening 23 leading from the chamber 20 downwardly and through the bushing 17 to the interior of the bearing. The other arm 12 is also of hollow construction and provided with side walls 24 and an inner 85 wall 25 flush with the inner edges of the side walls. A reinforcing web 26 extends from the rear wall 25 between the side walls for bracing and reinforcing the arm.

Near the upper end of the arm 12 the 90 inner wall 25 is provided with a vertically extending slot 27 opening through the wall and into which is fitted the boss 28 of a bearing block 29 disposed within the upper end of the arm 12. The bearing block 29 95 is provided with an opening therethrough and in which is seated a bushing or brass 30 provided on its inner end with an annular flange 31 adapted to seat against the boss 28.

The block 29 is supported in the upper end of the arm 12 by the boss 28 which engages upon the upper edge of the arm 25 and is held from tilting outward by a spring

clip 32. The spring clip 32 is in the form of a flat strip of metal having upon its upper end a hook 33 arranged to engage beneath a cross-bar 34 forming the upper end 5 portion of the inner wall 25, the clip 32 being bent to conform to the upper end and outer side of the bearing block 29.

The lower end of the clip is curved to project inwardly beneath the block 29 and 10 is removably held in such position by a transverse pin 35 secured through the side walls 24. The bearing block 29 is provided in its upper end with a chamber 36 adapted to receive a lubricant and which communicates with the interior of the bushing 30 through a passage 37 which leads downwardly through the block 29 and through the bushing.

The upper end of the chamber 36 is contracted to maintain a piece of waste 38 therein and provided with an inwardly extending shoulder or bead 39 to hold the waste from accidental displacement. The bearing block is offset inwardly at its upper 25 end and at its inner side to provide a shoulder 40 adapted to seat beneath the hook 33 for holding the bearing block from rising in the arm 12.

A shaft or spindle 41 is turned down and 30 rounded at opposite ends to fit in the bushings 17 and 30 respectively and is adapted to support a grooved wheel 42 between the arms. To assemble the parts it is only necessary to first position the wheel 42 between 35 the arms and hold it in registry with the fixed bushing 17. The shaft 41 is now inserted through the recess 27 in the arm 12, through the wheel 42, and finally seated in the bushing 17.

40 The bearing block 29 is now placed in the upper end of the arm 12 and fitted over the adjacent end of the shaft 41. The bearing block is now seated upon the upper end of the wall 25, the hook 33 of the spring clip 45 is engaged beneath the bar 34, and the clip 32 is now swung downwardly about the bearing block 29 and secured therebeneath by the pin 35.

In order to lubricate the bearings, it is 50 only necessary to withdraw the waste 21 from the upper end of the arm 11 and refill the chamber 20. The other bearing is inspected and filled by merely swinging the spring clip 32 upwardly upon the bar 34 55 when access may be readily had to the chamber 38. The spring clip 32 is of sufficient width to close the upper end of the bearing block and thus protect the waste and house in the lubricant.

60 It will be apparent that the device is relatively light in weight, is strong and well reinforced against all shocks and strain imposed upon it, and a device wherein the lubricant chambers may be readily reached for 65 replenishing and wherein the lubricant is

maintained from splashing out during use of the device.

I do not wish to be restricted to the size, form, and proportions of the various parts, and obviously changes could be made in the construction herein described without departing from the spirit of the invention, it being only necessary that such changes fall within the scope of the appended claims.

What is claimed is:

1. In a trolley harp, a pair of arms, one of said arms having a fixed bearing therein and the other arm having a recess opposite said bearing, a bearing block removably fitting in the recess of said second arm, a shaft seated in said bearing and in said bearing block, a wheel mounted on said shaft between the arms, and a spring clip removably fitting upon said second arm and engaging the bearing block for maintaining the same in place. 75

2. In a trolley harp, a pair of spaced apart arms, a fixed bearing in one arm, a removable bearing block in the other arm, yieldable means for detachably holding said block 90 in position, a shaft fitting in said bearing and bearing block, and a wheel mounted on the shaft.

3. In a trolley harp, a pair of arms, a bearing in one arm, said other arm having a recess therein opposite the bearing, a shaft adapted to be introduced through said recess and engaging at one end in said bearing, a removable bearing block fitting in said recess and adapted to engage the other 100 end of said arm, and spring means for removably holding said bearing block in position. 95

4. In a trolley harp, a pair of spaced apart arms, a shaft journaled at its ends in said arms, a trolley wheel fixed upon the shaft to turn therewith, said arms provided in their upper ends with lubricant receiving chambers and ducts leading from the chambers to the bearings of said shaft, said arms also having retaining shoulders in the open ends of said chambers adapted to yieldingly maintain a quantity of waste for the chambers. 105

5. A trolley harp comprising a U-shaped member having an upwardly opening cavity in one extremity and having a bearing therein at the lower end of the cavity and communicating therewith, the other end of said U-shaped member having a recess therein 115 opposite the bearing, a bearing block removably fitting in the recess, a shaft fitting at one end in said bearing and at its other end in said bearing block, said bearing block having an upwardly opening cavity in its upper end leading to the bearing, said cavities being adapted to receive lubricant and a quantity of waste, and the member and the bearing block each provided in the cavities thereof and at their upper edges with in- 120

125

130

wardly projecting beads adapted to reduce the upper ends of the cavities for holding the waste therein.

6. In a trolley harp, a yoke having a bearing in one side and a recess in the other side opposite the bearing, a shaft journaled at one end in the bearing and projecting at its other end through the recess, a trolley wheel mounted on the shaft, a bearing block 5 movably fitting in the recess and having a bearing adapted to receive the other end of said shaft, a spring clip interlocking with said yoke and engaging said bearing block to maintain the same in the recess, and 10 means for securing said clip in position.

7. In a trolley harp, a pair of arms, a bearing in one of said arms, a removable

bearing block fitted in the other arm, a shaft adapted to fit in said bearing and bearing block, spring means carried by said 20 other arm adapted to removably hold said bearing block in position, a wheel mounted on said shaft between the pair of arms, said first arm and the bearing block each being provided at its upper end with a chamber adapted 25 to receive a lubricant and having ducts leading from said chambers to the bearings, said chambers also being adapted to receive a quantity of waste, and shoulders carried by 30 said arms adapted to engage the waste for holding the waste in place whereby the lubricant is prevented from splashing out.

WILLIAM E. FIELDS.
